CLAIM

I claim an ornamental design for a coin depositing and dispensing apparatus, as shown and described.

DESCRIPTION

FIG. 1 is an upper left side perspective view looking downward at my new design;

FIG. 2 is a left side view of my new design;

FIG. 3 is a right side view thereof;

FIG. 4 is a front side view thereof;

FIG. 5 is a rear side view thereof;

FIG. 6 is a top view thereof; and,

FIG. 7 is a bottom view thereof.

The broken lines in the Figures depict parts of the coin depositing and dispensing apparatus that form no part of the Claim.

1 Claim, 7 Drawing Sheets
